UNITED STATES PATENT OFFICE.

GEORGE B. DYER, OF WASHINGTON, DISTRICT OF COLUMBIA.

IMPROVEMENT IN CORSETS.

Specification forming part of Letters Patent No. **154,027**, dated August 11, 1874; application filed June 13, 1874.

To all whom it may concern:

Be it known that I, GEORGE B. DYER, of Washington, in the county of Washington and District of Columbia, have invented a new and valuable Improvement in Corsets; and I do hereby declare that the following is a full, clear, and exact description of the construction and operation of the same, reference being had to the annexed drawings making a part of this specification, and to the letters and figures of reference marked thereon.

Figure 1 of the drawing is a representation of a front view of my corset, and Fig. 2 is a rear view of the same. Figs. 3, 4, 5, and 6 are detail views.

This invention has relation to ladies' corsets, wherein stay-bows are used inside of those portions which cover the breasts, for the purpose of giving beauty of shape to said portions. The ends of such stay-bows have hitherto been covered, and secured to the body of the corsets by means of pieces of cloth, forming pockets, which in a short time would wear out, and expose the ends of the bows, to the injury and inconvenience of the wearer. To remedy this objection, the nature of my invention consists in the employment of metal pockets, having clinching-spurs formed on them, by which they can be readily and securely fastened to the corset, as will be hereinafter explained.

In the annexed drawings, A designates the body of a corset, and B B the shoulder-straps. D D designate the expanded portions of the corsets, in which the breasts are inclosed; and a a represent the stay-bows, which may be made of whalebone or spring steel properly covered, and sewed to the inner sides of the said expanded portions, so as to extend from side to side of them, as shown in Figs. 1 and 2. E E designate the pockets or shields for inclosing the extremities of the stay-bows, and firmly keeping them in their places. These pockets, or sockets, are made of sheet metal struck up between suitable dies, and they are constructed with spurs e e e, which are passed through the cloth of the corset, around some of the vertical stays, and clinched, as shown in Fig. 5, thereby securing the pockets permanently in their places.

What I claim as new, and desire to secure by Letters Patent, is—

A corset provided with the spurred pockets E, made of metal, combined with the stay-bows a of the breast portions D, substantially as described.

In testimony that I claim the above I have hereunto subscribed my name in the presence of two witnesses.

GEO. B. DYER.
